UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT STOCK COMPANY OF FRANCE.

FIRING MECHANISM OF GUNS.

1,310,887.

Specification of Letters Patent. Patented July 22, 1919.

Application filed February 14, 1918. Serial No. 217,184.

To all whom it may concern:

Be it known that I, EUGÈNE SCHNEIDER, a citizen of the French Republic, residing at Le Creuzot, France, have invented a new 5 and useful Improvement in the Firing Mechanism of Guns, which is fully set forth in the following specification.

This invention has for its object to provide an improved firing mechanism for guns, 10 and to this end it consists in providing a combined striker-carrier and firing tube holder for the breech mechanisms of guns comprising a plastic breech gas check ring.

It has already been proposed to provide 15 the striker-carrier of such breech mechanisms with a head, in which the firing tube is engaged in such a manner as to produce on the one hand the proper insertion of the latter in the firing hole (formed in the movable head of the breech gas check ring) by the engagement of the striker-carrier in the shutter or other part of the breech block, and on the other hand inversely to effect 20 the extraction of the firing tube case by 25 the withdrawal of the striker carrier.

In known apparatus of this kind, the engagement of the firing tube is effected generally only along a fraction of the circumference of the collar of the firing tube case. 30 The consequence of this is that in withdrawing the striker-carrier, the result of this movement so far as it effects the pulling out of the firing tube case, is not satisfactory, while also the centering of the firing tube 35 case is not sufficiently assured.

The improvements of the present invention have for their object to avoid all those drawbacks. With this object, the firing tube holder is constituted by a disk fitting the 40 front face of the striker-carrier to which it is jointed by an eccentric pivot.

This disk is pierced at its center with a lodgment for the bottom of the firing tube case, and is adapted by displacement about 45 its pivot, to be brought into a position which allows the introduction of a fresh firing tube into the striker carrier, or the withdrawal of an empty case. A simple means of engaging the parts is provided between 50 the firing tube holder disk and the striker-carrier proper. This engagement is preferably effected at a point diametrically opposite to the pivot of the disk.

A practical embodiment of this invention is illustrated by way of example in the accompanying drawings in which:

Figure 1 is a longitudinal axial section of a gun breech provided with a breech block fitted with a plastic gas check ring, all being of any suitable known type, to which the present improved arrangement of combined striker-carrier and firing tube holder is applied.

Fig. 2 is a side elevation partly in section, drawn to a larger scale, of the combined striker-carrier and firing tube holder, the firing tube holder disk being charged with a firing tube and shown engaged with the striker-carrier.

Fig. 3 is a corresponding end view.

Fig. 4 is a side elevation of the parts shown in Fig. 2, wherein the said parts are shown in the position for allowing a fresh tube to be inserted or an empty tube to be withdrawn.

Fig. 5 is an end view of Fig. 4.

Referring first to Fig. 1, A is the breech end of a gun fitted with a breech block B comprising a plastic gas check ring C with a movable head D.

In the example shown, the movable head which is assumed to be screwed in a shutter E, comprises at its rear a nipple F for engaging the body of the firing tube case G. The shutter E has a lodgment for the engagement and assembling by any suitable means of the removable striker-carrier H combined with the firing tube holder I. In the example shown, it is assumed that this engagement is effected by means of a continuous screw-thread H¹ formed on the body of the striker-carrier and adapted to engage in a corresponding internal thread in the shutter E.

According to this invention the firing tube holder consists of a disk I (preferably though not necessarily in a single piece) in the center of which there is formed a lodgment of a section corresponding to that of the bottom of the firing tube case.

The disk I is pivoted to the removable striker-carrier H by means of an eccentric axel-pin I¹, this arrangement allowing of the disk being brought alternatively into the position shown in Figs. 4 and 5 for the insertion of a fresh firing tube or the with-

drawal of an empty case, or into the position shown in Figs. 2 and 3 where it is shown engaged with the striker-carrier before the whole is screwed into the shutter E.

5 In the preferred example shown, the engagement between the disk I and the body of the striker-carrier H is effected by means of a stud H² fixed in the front face of the body H, and a groove in the form of an 10 arc of a circle I² cut in the disk I. The curvature of this groove has for its center the pivot I¹ of the disk, and the bottom of the groove is preferably located at a point 15 diametrically opposite to the said pivot. Any other suitable device for securing the disk in position may be employed.

In the position of engagement the disk I is firmly engaged with the stud H² as clearly 20 shown in Figs. 2 and 3.

20 To bring the disk into one or the other of the positions shown, it is merely necessary to actuate it by means of the firing tube case G.

25 As a result of the construction the disk I is centered exactly in relation to the body of the striker-carrier H, so that the centering of the firing tube with relation to the nipple F of the movable head is necessarily assured as soon as the striker-carrier is in 30 its place in the shutter of the closed breech block.

The bottom of the firing tube case is held 35 all along its periphery in the disk I; this arrangement facilitating not only the maintenance of its centering during its insertion, but also the extraction of the empty case in

the withdrawal of the whole mechanism H—I—G.

As hereinbefore stated, the engagement or hooking of the eccentrically pivoted disk 40 I—I¹ may be effected by various means.

What I claim is:—

1. In the firing mechanism of a gun, the combination of a striker-carrier, a firing tube holder pivoted thereto, to swing transverse to the axis of said carrier, and means 45 for securing said holder in firing position on said carrier.

2. In the firing mechanism of a gun, the combination of a removable striker-carrier, 50 a pivot pin located eccentrically on said striker-carrier, a firing tube holder in the form of a disk mounted on said pivot pin, and a device on said striker-carrier for engaging and holding said firing tube holder 55 disk in position for firing.

3. In the firing mechanism of a gun, the combination of a removable striker-carrier, 60 a pivot pin located eccentrically on said striker-carrier, a firing tube holder in the form of a disk mounted on said pivot pin, a slot in said firing tube holder disk, and a stud on said striker-carrier adapted to engage said slot for holding said firing tube 65 holder disk in position for firing.

In testimony whereof I have signed this specification in the presence of two subscribing witnesses.

EUGÈNE SCHNEIDER.
